9 Claims. (Cl. 81—3)

1

My invention relates broadly to the dairy art and more particularly to a method and apparatus for use in the sanitation of inflations used in connection with automatic milking machines.

One of the objects of my invention is to provide an improved method of controlling bacteria in milk by thorough sanitation of the inflations used in connection with milking machines.

Another object of my invention is to provide an improved method for rapidly and effectively reversing the resilient inflation used in connection with milking machines for subjecting the interior wall of the inflation to a thorough cleansing operation for completely destroying bacteria which tends to collect in the interstices of the interior walls and annular flange of the inflation for insuring a high degree of sanitation in the inflation.

Still another object of my invention is to provide an improved apparatus which is capable of rapidly and effectively reversing an inflation with minimum of handling for subjecting the inside surfaces of the inflation to a scrubbing action for effectively removing all accumulated adhesions and bacteria.

Still another object of my invention is to provide a simplified construction of clamp which may be actuated to grip the annular flange of an inflation and operated through a linear path of movement for reversing the inflation and exposing the interior wall thereof for facilitating the scrubbing of the interior wall, the structure over which the clamp is movable being adapted for manipulating the inflation to restore the inflation to normal position after cleaning.

Still another object of my invention is to provide a simplified construction of support for mounting an inflation in a position in which the inflation may be mechanically reversed in its position for cleaning and thereafter restored to its original condition for reuse with a minimum expenditure of time and labor.

Other and further objects of my invention reside in the mechanical construction of the inflation inverter and reinverter tool as set forth more fully in the specification hereinafter following by reference to the accompanying drawings in which:

Figure 1 is a side elevational view of the tool of my invention prepared to receive an inflation for the purpose of inverting the inflation; Fig. 2 is a horizontal sectional view taken on line 2—2 of Fig. 1 and showing the vertically extending cylindrical casing and central rod of the tool in horizontal sectional view and illustrating the clamp

2

in top plan view; Fig. 3 is a horizontal sectional view taken on line 3—3 of Fig. 1; Fig. 4 is a side elevational view of the slideable removable clamp used in the structure of my invention; Fig. 5 is a vertical sectional view through the tool of Figs. 1—4 and showing the components of the tool in section; Fig. 6 is a side elevational view of a representative form of a large variety of types of resilient teat cups or inflations showing the cylindrical body structure thereof and the elongated discharge member of reduced section integrally connected therewith; Fig. 7 is a side elevational view of the tool of my invention with the teat cup or inflation applied thereto and illustrating the first step in the sanitation process where the teat cup or inflation is inserted over the central rod of the tool and extends downwardly concentrically within the vertically extending cylindrical casing; Fig. 8 is a vertical sectional view through the tool with the teat cup or inflation inserted in position as illustrated in Fig. 7; Fig. 9 is a side elevational view of the central cylindrical core member which is inserted over the central rod of the tool after the teat cup or inflation is inserted in the vertical extending cylindrical casing as represented in Fig. 8; Fig. 10 is a vertical sectional view through the tool showing the next succeeding step in the operation following the insertion of the teat cup or inflation shown in Figs. 7 and 8 where the clamp carried by the linearly slideable cylindrical member of the tool is moved to a position embracing the top of the resilient flange of the teat cup or inflation preparatory to a reversing operation; Fig. 11 is a vertical sectional view showing the next step in the operation of the tool in which the teat cup or inflation is reversed in its position to expose the interior wall thereof preparatory to a scrubbing operation; Fig. 12 is a vertical sectional view showing the inner wall of the teat cup or inflation being subjected to a brushing and cleaning operation in accordance with my invention; Fig. 13 is a plan view of the form of cleaning brush which I employ in the cleaning operation, the brush having two portions, one of which serves for cleaning the interior wall of the cylindrical portion of the teat cup or inflation while the other portion of which serves to clean the inner wall of the protruding discharge portion of reduced section of the teat cup or inflation; Fig. 14 is a diagrammatic view showing the brush of Fig. 13 being used for cleaning the interior wall of the protruding end of the teat cup or inflation; Fig. 15 is a fragmentary sectional view showing the

manner in which the teat cup or inflation after being cleaned in accordance with the several procedural steps is again applied to the tool of my invention preparatory for restoration to the original position of the teat cup or inflation; Fig. 16 is a fragmentary vertical sectional view showing the manner in which the teat cup or inflation is restored to its original position; Fig. 17 is an elevational view of a modified form of tool constructed in accordance with my invention and particularly suitable where transportation of the tool in a compact carrying case is desirable; Fig. 18 is a longitudinal sectional view taken through the tool of Fig. 17; Fig. 19 is a transverse sectional view taken on line 19-19 of Fig. 18; Fig. 20 is a transverse sectional view taken on line 20-20 of Fig. 18; Fig. 21 is an enlarged fragmentary and elevational view of the central rod employed in the structure of Figs. 17-20; Fig. 22 is a view similar to the view shown in Fig. 21 looking at the side of the rod where it is oriented 180° with respect to the brush shown in Fig. 21; Fig. 23 is a transverse sectional view taken on line 23-23 of Fig. 22; Fig. 24 is a transverse sectional view taken on line 24-24 of Fig. 22; Fig. 25 is a view showing the inflation reversed within the hand tool of Figs. 17-24 and Fig. 26 shows the central rod assembly removed for access to the interior wall of the inflation to allow cleaning thereof.

My invention is directed to a method and apparatus for improving sanitation in dairy operations. Heretofore the resilient teat cups or inflations used with milking machinery have often collected bacteria in the interstices of the interior resilient walls of the teat cup or inflation. The cleaning of the inside walls of these resilient teat cups or inflations has heretofore been difficult and time consuming and often because of the tediousness of the task, dairymen have overlooked this detail. Dirt and bacteria have accumulated on the inside walls of the teat cups or inflations and beneath the resilient flange of the teat cup or inflation. There have been instances where disease has been traceable to bacteria and germs accumulated in the teat cups or inflations from unhealthy udders of the cows. The structure of my invention provides a convenient fixture to which the used teat cups or inflations may be quickly applied, gripped in position and reversed to expose the inside walls thereof which may then be subjected to a thorough scrubbing action for removing all bacteria and germs. The same fixture is used for restoring the teat cup or inflation to its original position after it has been thoroughly cleaned. The entire operation is accomplished quickly and thoroughly. I have illustrated certain preferred embodiments of the tool of my invention but I desire that the disclosures herein be considered in the illustrative sense and not in the limiting sense as I realize that the principles of my invention may be carried out using structures of various modified forms.

Referring to the drawings in more detail reference character 1 designates the base of the structure of my invention centrally apertured at 2 for receiving the end stepped plug 3. The plug 3 has an end portion of reduced section at 3a that extends into aperture 2 and an upper portion 3b of larger section that provides a mounting means for the vertically extending cylindrical casing 4. The vertically extending cylindrical casing 4 is apertured adjacent the base

thereof as represented at 4a and 4b above the upper end of the portion 3b of plug 3 to permit the draining away of any accumulated fluid which may gravitate during the cleaning operation. The vertically extending cylindrical casing 4 stands vertically erect supported by the portion 3b of plug 3 and concentrically surrounding the central rod 5 that is mounted in plug 3. A spacer member 6 is disposed between rod 5 and the interior wall of vertically extending cylindrical casing 4 for maintaining the spaced relationship of the central rod 5 and the vertically extending cylindrical casing 4. The central rod 5 protrudes vertically upwardly beyond the peripheral edge 4a of the vertically extending cylindrical casing 4 in spaced relation to the interior walls of the vertically extending cylindrical casing 4.

A linearly slideable cylinder 7 concentrically surrounds vertically extending cylindrical casing 4 in spaced relation thereto. The linearly slideable cylinder 7 is provided with an annular spacer 7a in the lower end thereof which surrounds the vertically extending cylindrical casing 4 and serves as a guide for the linearly slideable cylinder 7 throughout its vertical path of movement longitudinally and axially of vertically extending cylindrical casing 4. The linearly slideable cylinder 7 is selected of such a length compared to the length or height of vertically extending cylindrical casing 4 and central rod 5 as will meet the average condition encountered in the dimensions of various makes and contours of teat cups or inflations. Inasmuch as these various makes differ from each other in specific dimensions and contours and particularly with respect to top flange structure, I provide an adjustable collar 8 which may be circumferentially expanded and contracted to grip the outside wall of linearly slideable cylinder 7 in the desired position for properly spacing the internal segmental flanges 9a of the pivoted clamps 9 which are pivotally mounted at 10 on brackets 11 that extend radially from the adjustable collar 8. The clamps 9 terminate at their lower ends in finger pressure lever 9b. The clamps 9 are biased by springs 12 which extend between the exterior side walls of linearly slideable cylinder 7 and around the pivotal mounting 10 and beneath the pressure lever 9b. The springs 12 tend to force the segmental flanges 9a toward the vertically extending cylindrical casing 4. The segmental flanges 9a of the clamps 9 and the other components of the clamp are all symmetrical in construction. I have shown three such clamps 9 disposed in positions around the adjustable collar 8 spaced 120° from each other. Under these conditions the segmental flanges 9a extend over a similar peripheral distance of 120°. The movement of the segmental flanges 9a toward the vertically extending cylindrical casing 4 is limited by the mutual abutment of the radially extending edges of the segmental flanges 9a which I have indicated at 9c and 9d in Fig. 2. The segmental flanges 9a depend downwardly concentrically with the outer surface of the vertically extending cylindrical casing 4 and spaced therefrom in order to provide proper engagement with the flange portion 14a of the teat cup or inflation 14 shown more particularly in Fig. 6. Thus the segmental flanges 9a are spaced both above the peripheral edge 7b of the linearly slideable cylinder 7 and spaced away from the exterior wall of the vertically extending cylindrical casing 4. The adjustable collar 8 is controllable by the

5

horizontally extending adjusting screw 15 which is provided with screw threads thereon which adjustably engage with slots 8a in one end of the adjustable collar 8 enabling the adjustable collar 8 to be circumferentially expanded and contracted sufficiently loosening the adjustable collar to enable the adjustable collar to be moved to the selected position and set therein for elevating the segmental flanges 9a sufficiently above peripheral edge 7b of linearly slidable cylinder 7 to properly engage the flange portion 14a of the teat cup or inflation 14.

As shown in Fig. 6 the representative teat cup or inflation 14 includes the flange portion 14a, the cylindrical portion 14b, the tapered portion 14c and the elongated discharge tubular portion 14d of reduced section. Teat cups and inflations offered by various manufacturers differ in specific detail and dimensions but generally they follow the contour depicted in Fig. 6 so that this form has been selected for illustrative purposes without intending to limit the application of my invention thereto.

In Fig. 7 I have shown the first step in the method of carrying out my invention wherein the teat cup or inflation 14 has the discharge end 14d thereof inserted over the end of central rod 5 and projected downwardly between the outside of central rod 5 and the inside wall of vertically extending cylindrical casing 4 with the annular peripheral edge 4a of the vertically extending cylindrical casing 4 providing an abutment stop for the tapered portion 14c of the teat cup or inflation. Fig. 8 shows in section the relationship of the teat cup or inflation to the central rod 5 and the vertically extending cylindrical casing 4 previously shown in side elevation in Fig. 7. The cylindrical portion 14b of the teat cup or inflation 14 projects substantially beyond the end of the central rod 5 in a vertical direction. Hence in order to strengthen the support for the resilient teat cup or inflation 14, I provide a cylindrical core member 16 having an axial recess 16a therein for receiving the end of central rod 5. The cylindrical core member 16 has a diameter which substantially fills the interior of the cylindrical portion 14b as shown in Fig. 8. As thus assembled the linearly slidable cylinder 7 is moved vertically to the position illustrated in Fig. 10 with the pressure levers 9b depressed to enable the segmental flanges 9a to clear the flange 14a of the teat cup or inflation 14 and to enable the peripheral edge 7b of the linearly slidable cylinder 7 to enter beneath the downturned edge of the flange 14a as represented in Fig. 10. That is to say, the position of adjustable collar 8 on the outside of linearly slidable cylinder 7 is so located that the clamps 9 when depressed by moving the pressure levers 9b inwardly toward the exterior wall of the linearly slidable cylinder 7 enable the segmental flanges 9a to move to a position above the annular flange 14a of the teat cup or inflation and enable the upper peripheral edge 7b of linearly slidable cylinder 7 to fit beneath the flange 14a as depicted in Fig. 10. When the pressure levers 9b are released, springs 12 force the segmental flanges 9a inwardly thus detachably clamping the flange 14a of the teat cup or inflation 14 to the upper end of the linearly slidable cylinder 7. The teat cup or inflation as thus clamped may now be manipulated by a quick downward movement shown in Fig. 11 in which the cylindrical portion 14b of the teat cup or inflation is inverted and the inside walls exposed as shown in Fig. 11.

6

Throughout this operation the discharge end portion of the teat cup or inflation shown at 14d remains clamped between the central rod 5 and the inside of the vertically extending cylindrical casing 4. Fig. 12 shows the next succeeding step in the operation in which the pressure levers 9b have again been depressed enabling the segmental flanges 9a to clear a position beneath flange 14a so that the linearly slidable cylinder 7 is wholly detached from the inflation and moved downwardly to its original position with respect to the base 1.

The brush shown in Fig. 13 is now applied to the exposed inside walls of the cylindrical portion 14b of the teat cup or inflation as represented in Fig. 12 for thoroughly scrubbing the said inside walls for removing bacteria and germs. A suitable cleansing solution is employed in facilitating this operation. The collection of any accumulated dirt beneath the flange 14a is also removed. The brush used for this purpose may have a variety of forms. I have illustrated in Fig. 13 one typical form for the brush consisting of a pair of arms 17 and 18 pivoted at 19 and having handle extensions 17a and 18a thereon. The arms 17 and 18 are each substantially semi-circular in contour and carry sets of bristles 18b and 17b adapted to engage the exposed surface of the cylindrical portion 14b of the inflation 14 for thoroughly scrubbing the interstices thereof for dislodging bacteria and germs which may have accumulated therein. The handle portion 17a of the brush is extended as shown at 17c to form an elongated slender brush 17d of a size 35 which may be inserted through the interior of the top end of reduced section of the inflation at 14d. This operation is shown more clearly in Fig. 14 where the inverted inflation is wholly removed from the tool to permit reciprocative action of brush 17d through the interior walls of the discharge end 14d of reduced section of the inflation 14.

As thus thoroughly cleaned the inverted inflation is ready for restoration to its original condition and for this purpose the inflation is restored to the fixture in the position shown in Fig. 15 where at this time the discharge end of the teat cup or inflation at 14d is inserted over central rod 5 in a reverse position as compared to the position in which the inflation was removed from the fixture in Fig. 12. The tapered portion 14c of the teat cup or inflation now engages and hugs the upper peripheral extremity 4a of the vertically extending cylindrical casing 4 as shown in Fig. 15. In this position the flange 14a may be gripped and the cylindrical portion 14b rolled downwardly over the vertically extending cylindrical casing 4 as represented in Fig. 16 thus restoring the inflation to its original condition. The structure thus described is ideally suited for large scale dairy operations. There are situations in which a more readily portable unit is desirable and for this purpose I may utilize the form of my invention shown in Figs. 17-24. In this arrangement a housing formed by a pair of metallic tubes 20 and 21 is provided. The tube 20 has an annular flange 22 formed thereon with bayonet pins 22a and 22b extending therefrom and coacting with a sleeve-like header 23 having bayonet slots 23a and 23b formed therein.

The header 23 serves as a confining means for the flange 14a of the teat cup or inflation and maintains the flange 14a over the peripheral edge 29a of the metallic tube 20 with the cylindrical portion 14b of the teat cup or inflation extending

downwardly within the tube 20 and with the discharge end 14d of reduced section extending into the interior of tube 21. The inclined wall section 14c of the inflation interconnecting the cylindrical portion 14b and the reduced section discharge end portion 14d facilitates reversal of the inflation as will be hereinafter explained in more detail. Tube 21 is slidable within tube 20 under control of the central rod 25. The central rod 25 has the end thereof shaped in quadrantal sections as shown more particularly in Figs. 21-24 with a slot 25a formed therein and a quadrantal keyhead 25b connected therewith, the central rod 25 is capable of being revolved by means of handle 25c to move the keyhead 25b into engagement with the semi-cylindrical aperture 21a in the closed end of tube 21 enabling tube 21 to be drawn longitudinally through aperture 20b in cylinder 20.

The central rod 25 extends through the discharge end 14d of the teat cup or inflation and through the inclined wall section 14c and cylindrical portion 14b and carries the slidable cylindrical member 26 which serves as a core to support the interior walls of the cylindrical portion 14b of the teat cup or inflation during the process of reversal of the teat cup or inflation. With the teat cup or inflation inserted into the tubes 20 and 21 as shown in Fig. 18 and the header 23 latched in position over the bayonet pins 22a and 22b the central rod 25 is grasped by handle 25c and drawn longitudinally of the tubes 20 and 21. This operation produces a reversal of the teat cup or inflation as shown in Fig. 25 where tube 21 has its peripheral end 21b drawn against the inclined wall portion 14c of the teat cup or inflation and as the longitudinal movement of tube 21 continues the cylindrical portion 14b of the teat cup or inflation is reversed upon itself in the position illustrated in Fig. 25. When the entire limit of travel of tube 21 is reached the tube 20 is entirely cleared of the inflation or teat cup and the inside wall of the cylindrical portion 14b of the teat cup or inflation is exposed for scrubbing and cleaning. During this operation the cylindrical member 26 serves as a follower abutment for the turned over portion 14c of the teat cup or inflation.

The reversed teat cup or inflation is now ready to be wholly removed from the tube 20. This is accomplished by releasing the header 23 which is moved out of obstructing position beneath handle 25c enabling the tube 20 to be detached. The reversed teat cup or inflation after cleaning of the interior surface of cylindrical portion 14b may be wholly removed from the tool and the interior of the discharge portion 14d of reduced section subjected to interior cleaning using the brush described in connection with Fig. 13 in the manner disclosed in Fig. 14. While the inside surface of the inflation is now accessible for cleaning it is also practical to clean the inside of the flange portion 14a to eliminate secretions and bacteria which may have collected thereunder. After thus cleaning the inflation or teat cup the inflation or teat cup may be restored to the tool in the assembly illustrated in Fig. 26 by suitable manipulation of the central rod 25 through the latching end of tube 21 at 21a and then the teat cup or inflation rolled back to its original position in the form illustrated in Fig. 18. The tool is then disassembled and the inflation removed and is immediately ready for reuse.

My invention is broader than the apparatus

which I have shown for carrying out the process described wherein as I employ a novel method and principle which I desire to protect in the appended claims, that is the mounting of the resilient inflation in such manner that restraining forces are imposed upon the inflation in all transverse directions while the reversing force is impressed upon the inflation in a longitudinal direction. The manner of mounting the inflation for preventing displacement of the resilient walls thereof due to distortion insures the longitudinal rolling of the resilient material of the inflation in a way that the quick reversing operation may be effected. Both the inside and outside walls of the inflation are restrained against transverse displacement or bulging so that the longitudinal forces applied to the inflation are entirely utilized in effecting a reversal position of the walls of the inflation.

My invention also includes the novel construction of brush described herein for the scrubbing of the exposed inside wall of the inflation.

Both forms of the structure of my invention have been found to be highly practical and successful in operation. While I have described but two embodiments of my invention, I realize that modifications may be made in the structural arrangement and assembly of the parts of my device and I accordingly desire that it be understood that no limitations upon my invention are intended other than may be imposed by the scope of the appended claims.

What I claim and desire to secure by Letters Patent of the United States, is as follows:

1. An apparatus for reversing inflations comprising a base, a central rod extending vertically from said base, a vertically extending cylindrical casing surrounding said rod in spaced relation thereto and terminating below the end thereof, a linearly slidable cylinder concentrically positioned over said cylindrical casing and carrying a multiplicity of clamps thereon, said clamps being adapted to grip the peripheral edge of a resilient tubular member inserted between said rod and said cylindrical casing and reverse the position of said resilient tubular member and turn the inside thereof outside.

2. An apparatus for reversing inflations as set forth in claim 1 in which said clamps may be longitudinally adjusted in position with respect to the end of said linearly slidable cylinder for accommodating said clamps to grip the peripheral edge of a resilient tubular member where the said peripheral edge may vary in thickness over wide limits.

3. An apparatus for reversing inflations as set forth in claim 1 in which said clamps are spaced around said linearly slidable cylinder at distances of substantially 120° from each other.

4. An apparatus for reversing inflations as set forth in claim 1 including resiliently biased lever members which are normally maintained in a position for urging said clamps in a radially inward direction.

5. An apparatus for reversing inflations as set forth in claim 1 in which said clamps each have segmental gripping members thereon with opposite ends of the segmental gripping members forming mutual abutments for limiting the radially inward movement of said clamps with respect to the resilient tubular member clamped thereby.

6. An apparatus for reversing inflations comprising a base, a central rod extending vertically from said base, a vertically extending cylind-

drical casing surrounding said rod in spaced relation thereto and terminating below the end thereof, a linearly slideable cylinder concentrically positioned over said cylindrical casing, a band member attached to said cylinder, a multiplicity of lever members pivotally mounted on said band member, said levers terminating in inwardly directed clamping portions upon the end of said cylinder, spring means interposed between said lever members and said cylinder for normally urging said lever members to a position in which said clamping portions are maintained in positions adapted to grip the peripheral edge of a resilient tubular member inserted between said rod and said cylindrical casing and reverse the position of said tubular member and turn the inside thereof outside by a longitudinal movement of said linearly slideable cylinder with the peripheral edge of the resilient tubular member clamped thereby for subjecting the said inside surface to a cleaning operation.

7. An apparatus for reversing inflations as set forth in claim 6 in which said band member is adjustable toward or away from the end of said linearly slideable cylinder for controlling the spacial relation of said clamps with respect to the end of said linearly slideable cylinder and adapting the said clamps to grip the peripheral edge of a resilient tubular member where the depth of the peripheral edge may vary over wide limits. 30

8. An apparatus for reversing inflations as set forth in claim 6 in which said clamping portions are constructed of segmental shape flat faces each having curved edge portions with inwardly directed flange portions operative to engage the central portion of the peripheral edge of the resilient tubular member clamped thereby.
9. An apparatus for reversing inflations as set forth in claim 6 which includes a cylindrical core member having an axial recess therein which engages the end of the central rod that extends from the base and supports the wall of the resilient tubular member during the reversing operation thereof.
